COMPRESSOR SHUT-OFF VALVE
MECHANISMSteve Schnell, St. Louis, Mo., assignor to Wagner
Electric Corporation, St. Louis, Mo., a corpora-
tion of Delaware

Application July 5, 1938, Serial No. 217,488

13 Claims. (CL 230—30)

My invention relates to valve mechanism and more particularly to valve mechanism for shutting off the intake of a compressor to unload it.

One of the objects of my invention is to provide an improved shut-off valve mechanism for such association with a compressor and its receiver that the compressor intake will be automatically closed when the pressure in the receiver reaches a predetermined maximum value and automatically reopened when the pressure in the receiver drops to a predetermined minimum value.

Another object of my invention is to provide improved means for quickly relieving the pressure acting on the movable shut-off valve member of the mechanism when the receiver pressure drops to the predetermined minimum value so that said valve member will be caused to be positively opened under the action of its biasing spring.

Still another object of my invention is to so combine and arrange the parts of the valve mechanism that they will operate in an efficient and reliable manner.

Other objects of my invention will become apparent from the following description taken in connection with the accompanying drawings showing two embodiments in which Figure 1 is a view showing one form of my shut-off valve mechanism associated with a compressor and its receiver; Figure 2 is an enlarged longitudinal cross section of the valve mechanism showing details thereof; Figure 3 is an enlarged longitudinal cross-sectional view of a modified construction; and Figure 4 is a left-hand end view of the valve mechanism shown in Figure 3.

Referring to the drawings in detail, the air compressor 1, with which I have illustrated my shut-off valve mechanism as being associated, is of the rotary type having a stator 2 and an eccentrically mounted rotor 3 provided with a plurality of blades 4 (one only being shown). The stator has an intake port 5 and an outlet port 6, the latter opening into an oil dome 7 which is connected to a pressure tank 8 by means of a conduit 9, the oil dome and the pressure tank both being considered as parts of the receiver of the compressor. The outlet of the compressor has associated therewith a check valve 10 for preventing back flow of compressed fluid and the outlet of the dome is controlled by another check valve 11. The pressure tank 8 is adapted to be connected by a conduit 12 with any suitable fluid pressure-actuated system (not shown) which

may be employed to operate any mechanism desired such as a braking mechanism.

In compressors of the type described, which are of well-known construction, it is desirable to automatically prevent the compressor from compressing fluid after the fluid in the receiver has been placed under a predetermined maximum pressure. This is best accomplished by shutting off the intake port so the air or other fluid which is being compressed by the compressor is not permitted to enter the compressing chamber. It is also desirable that the intake port not only be automatically closed at the proper time but that it also be reopened whenever the pressure in the receiver drops.

In accordance with my invention, I have provided an improved valve mechanism 13 which is associated with the compressor intake and also with the compressor oil dome and the receiver whereby the desired operation of the valve mechanism is accomplished. The valve mechanism comprises a casing 14 secured to the compressor by an attaching flange 15. The casing is provided with a cylindrical bore 16 and this bore is connected to the compressor intake by a passage 17. The inlet passage 18 for the bore is associated with an air cleaner 19 for cleaning the incoming air. Within bore 16 is a slideable valve member 20 carrying a rubber member 21 for cooperation with a seat 22 in the bore for closing off communication between passages 17 and 18. The forward end of the piston is sealed by a packing cup 23 in order to prevent leakage of fluid from chamber 24 closed by a plug 25. Associated with the forward end of the piston within chamber 24 is a valve element 26 mounted on a tubular projection 27 and this valve element is adapted to cooperate with a rubber seat 28 to prevent communication from chamber 24 to a passage 29 in plug 25 leading to a chamber 30, the passage being aligned with the tubular member 27. The slideable valve member 20 is formed with a bore 31 also communicating with the tubular projection 27 and within this bore is a plunger 32 having a projecting rod 33 reciprocably mounted in the nut 34 threaded in the right end wall of the casing. The plunger is formed with a flange 32' for engaging the rubber member 21 to seal the plunger in bore 31. A spring 35 surrounds rod 33 and is interposed between plunger 32 and nut 34 in order to bias flange 32' of the plunger against the valve member 20 and valve member 20 to a position where the valve member is unseated. The spring 35

also normally maintains the valve element 26 in engagement with seat 28.

Within chamber 30 of plug 25 is a plunger 36, the right end of which carries a valve element 37 for closing passage 29. Associated with the plunger is a diaphragm 38 for preventing communication from a chamber 39 to chamber 30, the former communicating with a passage 40 connected to a conduit 41 leading from the pressure tank 8 of the compressor. The plunger 36 is acted upon by a spring 42 for maintaining the valve element 37 unseated and the left end of the plunger in engagement with the surface surrounding the opening 40. The plug 25 is formed with a suitable outlet passage 43 for placing chamber 30 in communication with the atmosphere.

The chamber 24 is connected to the oil dome 7 of the compressor in order that the forward end of valve member 20 may at all times be subject to the pressure of the fluid in the dome portion of the receiver. The connection comprises a conduit 44 and a passage 45 leading into chamber 24, this passage being considerably smaller than passage 29.

The valve mechanism may be set to automatically shut off the compressor intake at any desired pressure in the receiver. For the purpose of this description it is assumed that the maximum pressure desired in the receiver is one hundred pounds per square inch. The spring 35 under these conditions is adjusted by nut 34 to prevent valve member 20 from being moved to closed position except when the pressure in chamber 24 is slightly greater than one hundred pounds per square inch. Such a setting of the spring will permit plunger 32 to be moved relative to valve member 20 when the pressure in bore 31 is about seventy-five pounds per square inch, the area of the plunger acted upon by this pressure being less than the area of the valve element which is acted upon by the pressure in chamber 24. Spring 42 for plunger 36 is of such strength that the plunger will not be moved to closed position until the pressure in chamber 39 is approximately ninety pounds per square inch.

With the compressor operating and the valve parts in the position shown in Figure 2, air will be free to enter the compressor and be forced out into the oil dome and into tank 8. When the pressure in the receiver reaches the value of ninety pounds per square inch, plunger 36 will be moved to the right and passage 29 closed by valve element 37. Continued operation of the compressor will bring the pressure in the oil dome and the tank up to one hundred pounds per square inch. When this pressure is reached, there will also be one hundred pounds per square inch pressure in chamber 24. This will be sufficient to overcome spring 35 and move valve member 20 to the right toward closed position. As soon as valve member 20 is moved, it will unseat valve element 26, thereby permitting fluid under one hundred pounds per square inch pressure to enter the passage of the tubular projection 27 and bore 31 and become effective upon plunger 32 in addition to the end surface of valve element 26. The flange 32' of the plunger will now be moved away from the rubber member 21 after the valve member has become seated. This will result in the pressure in chamber 24 dropping to a value of seventy-five pounds per square inch which is sufficient to hold the valve member 20 seated. The drop in pressure in chamber 24 also results in a drop in pressure in

the compressor dome which is desirable as it relieves pressure on the oil tending to force it into the compressor which is undesirable when the compressor is idling. It is to be noted that the valve member, after it has initially moved and unseated valve element 26, permits additional area to be subjected to the pressure in chamber 24, thus causing a very rapid movement of the valve toward its seat.

If the pressure in the tank drops to ninety pounds per square inch as a result of fluid being used therefrom, spring 42 will become effective to move plunger 36 to the left and unseat valve element 37. This will immediately cause a release of pressure in chamber 24 through passage 29, chamber 30 and outlet passage 43 since passage 29 is larger than passage 45 and, therefore, the fluid under pressure in chamber 24 will escape faster than the fluid under pressure being supplied through passage 45. The spring 35 will now become operative to move valve member 20 to the left away from seat 22 and reopen the intake of the compressor to atmosphere by way of passages 17 and 18. The parts of the valve mechanism will now assume the position shown in Figure 2 and the compressor will again build up the pressure in the dome and the tank to the desired maximum pressure of one hundred pounds per square inch wherein the valve mechanism will again function in a manner already described to shut off the compressor.

It is to be noted that the valve mechanism is so constructed that there will be a rapid closing movement of valve member 20 once it is initially moved by the maximum pressure in the oil dome. It is also to be noted that as soon as the pressure in the tank drops to a predetermined minimum value of ninety pounds per square inch, the pressure acting upon valve member 20 to shut off the compressor is immediately relieved and the spring is effective to immediately fully open the compressor to atmosphere. In the arrangement of the parts shown there is no possibility of valve member 20 "fluttering" on and off its seat 22. Once the valve element is seated, it will remain so and will not become unseated until the dome pressure drops to the minimum value of ninety pounds per square inch. When this pressure is reached, the pressure tending to hold the valve seated will be immediately exhausted to atmosphere and the valve member quickly and positively moved to its open position.

In the construction shown in Figures 3 and 4, the valve casing 47 is provided with a chamber 48 which is connected by a passage 49 through the attaching flange 49' to the intake of the compressor and a passage 50 in a fitting member 50' to the atmosphere through the air cleaner. Within chamber 48 is a valve seat 51 for co-operation with the movable valve member 52 for closing off communication from the atmosphere to the intake of the compressor. The valve member is biased to its open position against a stop 53 by a spring 54. The forward end of the piston has associated therewith a sealing cup 55 and at the end of this piston is a chamber 56.

The right-hand end of the casing is formed with a bore 57 having a reduced portion 58 communicating with chamber 56 by means of passage 59. Slidably in bore 57 is a piston 60 having a portion projecting into the small bore 58 with which is associated a sealing cup 61. The piston is backed by a spring 62 which normally maintains the piston against shoulder 63. The 75

tension of the spring is adapted to be adjusted by a nut 64 carried by a plug 65 threaded into bore 57. The central part of the piston is formed with a bore 66 and slidably therein is a plunger 67 carrying a valve element 68 for closing passage 59, the valve element being held on its seat by a spring 69 operating upon plunger 67. The plunger 67 is guided by a sleeve 70 carried by the piston and the end of this sleeve is so related to the head of the plunger that the plunger will not be moved with the piston 60 until the piston has moved a predetermined distance to the right. When the plunger is picked up by the piston, it will unseat valve element 68. The small bore 58 communicates with a conduit 71 which is connected to the receiver of the compressor.

The casing is also provided with an additional bore 72 which communicates with chamber 57 and with an atmospheric port 73 by means of a passage 74. Within the bore is a valve element 75 biased by a spring 76 toward the position to close the passage. The valve element is formed with a stem 77 which is adapted to be engaged by the piston 60 when it is against the shoulder 63 to thereby maintain the valve element unseated.

With the parts in the position shown, air is free to enter the compressor by way of passages 50 and 49. When the pressure in the receiver reaches one hundred pounds per square inch, the pressure acting against the end of piston 60 will be sufficient to overcome spring 62 and move the piston to the right. When piston 60 moves to the right, the valve element 75 will first be seated and then valve element 68 unseated. The chamber 56 will now be closed off from communication with the atmosphere and connected to the receiver, and the pressure in the chamber will be sufficient to move the valve member 52 to the left against seat 51. The compressor will now be shut off from the atmosphere and will run under no load.

When the pressure in the receiver drops to a predetermined value, say ninety pounds per square inch, spring 62 will be strong enough to move piston 60 to the left. This will first cause valve element 68 to become seated and close off communication between chamber 56 and the receiver. As the piston continues to move to the left, valve element 75 will be unseated by the piston engaging stem 77. The fluid pressure in chamber 56 will now be exhausted to atmosphere through passage 73 and spring 54 will then be effective to quickly unseat the valve member 52. Pressure may now be built up in the receiver to the maximum value of one hundred pounds per square inch and the valve mechanism will again operate to shut off the compressor.

Being aware of the possibility of modifications in the particular structure herein described without departing from the fundamental principles of my invention, I do not intend that its scope be limited except as set forth by the appended claims.

Having fully described my invention, what I claim as new and desire to secure by Letters Patent of the United States is:

1. In a unitary valve mechanism of the class described for association with the intake of a compressor and the fluid pressure receiver therefor, a casing having a port for communication with the compressor intake, a movable member reciprocable in said casing and adapted to be acted upon by fluid pressure from the receiver

for closing the port, a spring for biasing the member to open position and preventing movement of the member to closed position except when acted upon by a predetermined pressure, means comprising the movable member and a portion of the casing within which it reciprocates for forming a chamber, conduit means in the casing for connecting the chamber to the receiver, means including a passage for connecting the chamber to atmosphere independently of the conduit means, a valve for controlling said passage, and means operable by pressure from the receiver for closing said last named valve. 10

2. In a unitary valve mechanism of the class described for association with the intake of a compressor and the fluid pressure receiver therefor, a casing having a port for communication with the compressor intake, a movable member reciprocable in said casing and adapted to be acted upon by fluid pressure from the receiver for closing the port, a spring for biasing the member to open position and preventing movement of the member to closed position except when acted upon by a predetermined pressure, means comprising the movable member and a portion of the casing within which it reciprocates for forming a chamber, conduit means in the casing for connecting the chamber to the receiver, means including a passage for connecting the chamber to atmosphere independently of the conduit means, a valve for controlling said passage, and means comprising a spring for causing said valve to be opened when the pressure in the receiver drops a given amount below the predetermined pressure required to move the movable member. 20

3. In valve mechanism of the class described for association with a compressor and a receiver connected to the exhaust side thereof, a casing having a port for communication with the intake of the compressor, a movable valve member in said casing for controlling the port, a spring for biasing the member to open position, said member forming a movable wall of a chamber which is adapted to be connected to the receiver 45 whereby a predetermined pressure will move the movable valve member to close the port, means comprising a passage for connecting the chamber to atmosphere, a valve for said passage, a spring for normally biasing the valve to open 50 position, and means operable by pressure from the receiver for closing said valve when the pressure therein is less than the pressure necessary to move the movable valve member to close the port associated with the intake of the compressor. 55

4. In valve mechanism of the class described for association with a compressor and its receiver, a casing having a port for communication with the intake of the compressor, a movable valve member in said casing for controlling the port, a spring for biasing the member to open position, said member forming a movable wall of a chamber which is adapted to be connected to the receiver, means operable by fluid pressure 60 from the receiver for moving said valve member against said spring to closed position, said means comprising a surface of said valve member acted upon by a predetermined pressure from the receiver to initially move the valve member toward 65 closed position, means operable upon initial movement of the valve member for causing an additional surface of the valve member to be acted upon by said predetermined pressure, means forming a relief passage from the chamber, a 70 75

valve for said passage, and means for maintaining said valve closed by a fluid pressure from the receiver which is of lower value than the predetermined pressure, whereby the relief passage from the chamber will be closed prior to any movement of the valve member toward closed position.

5. In a valve mechanism of the class described for association with a compressor and its receiver, a casing having a port for communication with the intake of the compressor, a movable valve member in said casing for controlling the port, a spring for biasing the member to open position, said member forming a movable wall of a chamber which is adapted to be connected to the receiver, means operable by fluid pressure from the receiver for moving said valve member against said spring to closed position, said means comprising a surface of said valve member acted upon by a predetermined pressure from the receiver to initially move the valve member toward closed position, means operable upon initial movement of the valve member for causing an additional surface of the valve member to be acted upon by said predetermined pressure, means forming a relief passage from the chamber, a valve for said passage, a spring for biasing the valve open, and means for maintaining said valve closed against the bias of its spring by a fluid pressure from the receiver which is of lower value than the predetermined pressure, whereby the relief passage from the chamber will be closed prior to any movement of the valve member toward closed position.

6. In valve mechanism of the class described for association with a compressor and its receiver, a casing having a port for communication with the intake of the compressor, a movable valve member in said casing for controlling the port, a spring for biasing the member to open position, means comprising a portion of the movable valve member and the casing for forming a chamber which is adapted to be connected to the fluid pressure receiver, means comprising another portion of the valve member for forming a second chamber, valve means for connecting the second chamber to the first chamber when said movable valve member is initially moved toward closed position by a predetermined pressure, means forming a relief passage from the chambers, a valve for said passage, a spring for biasing the valve open, and means for maintaining the valve closed against the bias of its spring by fluid pressure from the receiver which is of lower value than the value of the predetermined pressure, whereby the relief passage will be closed prior to the movement of the valve means to connect the two chambers.

7. In valve mechanism of the class described for association with a compressor and its receiver, a casing having a port for communication with the intake of the compressor, a movable valve member in said casing for controlling the port, a spring for biasing the member to open position, means for moving said movable valve member to closed position by a predetermined pressure from the receiver, and means for causing said spring to exert less force on the valve member tending to bias the valve member to open position after the valve member is moved to closed position.

8. In valve mechanism of the class described for association with a compressor having an oil dome and a pressure tank connected to the exhaust side of the compressor and a check valve for pre-

venting return flow of fluid from the tank to the oil dome, a casing having a port for communication with the intake of the compressor, a movable valve member in said casing for controlling the port, a spring for biasing the member to open position, means for moving said movable valve member to closed position by a predetermined pressure from the oil dome, and means operable when the valve member is in closed position for permitting a drop in the pressure in the oil dome.

9. In valve mechanism of the class described for association with a compressor having an oil dome and a pressure tank connected to the exhaust side of the compressor and a check valve for preventing return flow of fluid from the tank to the oil dome, a casing having a port for communication with the intake of the compressor, a movable valve member in said casing for controlling the port, a spring for biasing the member to open position, means for moving said movable valve member to closed position by a predetermined pressure from the oil dome, and means comprising a movable member operable by the fluid pressure from the oil dome for permitting a reduction of pressure in the oil dome.

10. In valve mechanism of the class described for association with a compressor having an oil dome and a pressure tank connected to the exhaust side of the compressor and a check valve for preventing return flow of fluid from the tank to the oil dome, a casing having a port for communication with the intake of the compressor, a movable valve member in said casing for controlling the port, a spring for biasing the member to open position, means for moving said movable valve member to closed position by a predetermined pressure from the oil dome, and means comprising a movable member operable by the fluid pressure from the oil dome for permitting a reduction of pressure in the oil dome.

11. In valve mechanism of the class described for association with a compressor and its receiver, a casing having a port for communication with the intake of the compressor, a movable valve member in said casing for controlling the port, a spring for biasing the member to open position, said member forming the movable wall of a chamber, a conduit for connecting the chamber with the receiver, a valve for controlling said conduit, a second conduit for connecting the chamber with the atmosphere, a valve for the last named conduit, and means operable by a predetermined pressure from the receiver for permitting the last named valve to be closed and subsequently opening the first named valve.

12. In valve mechanism of the class described for association with a compressor and its receiver, a casing having a port for communication with the intake of the compressor, a movable valve member in said casing for controlling the port, a spring for biasing the member to open position, said member forming the movable wall of a chamber, means comprising a movable member for forming a second chamber adapted to be con-

5 nected with the receiver, a spring acting on the movable member in the second chamber, a conduit connecting the chambers, a valve for controlling the conduit, means operable by a pre-determined fluid pressure in the second chamber for causing the movable member therein to move said valve to open position, means forming a relief passage for the first chamber, a valve for said passage, a spring for biasing said valve closed, and means for causing said last named 10 valve to be held open against the bias of its spring by the movable member in the second chamber when it is in a position permitting said first named valve to be closed.

15 13. In valve mechanism of the class described for association with a compressor and its receiver, a casing having a port for communica-

tion with the intake of the compressor, a movable valve member in said casing for controlling the port, a spring for biasing the member to open position, said member forming the movable wall of a chamber, a conduit for connecting the chamber with the receiver, a valve for said conduit, a conduit for connecting the chamber with the atmosphere, a valve for the last named conduit, a movable member subject to fluid pressure from the receiver, a spring for biasing said member 10 against the action of the pressure, and means operable by the movement of the movable member against its spring for first permitting the second valve to close and subsequently opening the first valve.

STEVE SCHNELL.
